METHOD OF MAKING AND ATTACHING
FURNITURE GLIDESErving B. Morgan, Grand Rapids, Mich., assignor
to American Seating Company, Grand Rapids,
Mich., a corporation of New Jersey

Application May 3, 1951, Serial No. 224,301

2 Claims. (Cl. 29—148)

1

The present invention relates to furniture glides.

The primary objects of the invention are to provide improved furniture glides which will not make unsightly impressions in, nor otherwise mar, floors made of composition, linoleum or the like; to provide such furniture glides which are especially suitable for chairs and which will not mar floors even though the chair is tipped rearwardly by the occupant thereof thus throwing the occupant's entire weight on the rear legs of the chair; to provide such glides which are cushioned to absorb some of the impact when a person sits in the chair; to provide an improved furniture glide in which the outer or floor-contacting member is case-hardened to increase its wearing quality; and in general to provide such a furniture glide which comprises few parts and which may be quickly assembled on an article of furniture, which is reasonably economical in manufacture and which is attractive in appearance.

An illustrative embodiment of the invention is shown in the accompanying drawings, wherein:

Figure 1 is a front and side perspective view of a chair equipped with the new furniture glides;

Figure 2 is an enlarged fragmentary horizontal sectional view taken on line 2—2 of Figure 1 and indicating one of the new glides;

Figure 3 is a vertical sectional view of the same taken on line 3—3 of Figure 2;

Figure 4 is a side elevational view of the chair shown in Figure 1, tipped rearwardly;

Figure 5 is a vertical sectional view of one of the rear glides of the chair as it would appear when the chair is tipped rearwardly as indicated in Figure 4;

Figure 6 is a composite perspective view showing the parts of the new furniture glide prior to their assembly;

Figures 7, 8, 9 and 10 are enlarged fragmentary vertical sectional views illustrating progressive steps in the assembly of the new glide with a chair.

Referring now in detail to these drawings wherein like parts are designated by the same numerals in the several views, the chair shown in Figures 1 and 4 generally comprises sheet metal side frames 11 connected by rails 12, 13 and provided with a seat 14 and back rails 15. Along the bottom edge of each side frame 11 of the chair are an inwardly turned flange 16, and the four furniture glides for the chair are mounted on these flanges 16, two at the front and two at the rear. The glides are generally designated 17 and being identical in construction and as-

sembly only one of them is hereinafter described in detail, being the one at the right rear of the chair as shown in Figure 1.

Prior to its assembly with the chair, each glide 17 comprises the parts shown separately in Figure 6, being a floor-contacting outer member or shell 18, a fastening member or rivet 19, an inner washer member or spider 20, and an annular rubber cushion member 21.

The floor-contacting outer shell 18 comprises a sheet metal disk which is formed to provide a slightly downwardly dished middle body portion 22 and an upwardly and inwardly curled peripheral retaining flange 23 which surrounds or defines a central opening 24 through which the interior of the shell is accessible. After the outer shell 18 is thus formed, but prior to its assembly with the other parts of the glide, it is case-hardened to give it the necessary wearing quality.

The inner spider member 20 of the glide comprises a sheet metal washer which is formed to provide an upwardly dished middle body portion 25 having a central aperture 26 therethrough, and leg portions 27 extending radially outwardly from the middle body portion 25. When the spider 20 is initially formed, the leg portions 27 thereof are downwardly turned as shown in Figures 6 and 7 in order to reduce the overall diameter of the spider so that it may be inserted within the outer shell 18 through said shell's central opening 24.

The rivet 19 is of more or less conventional form comprising a shank 28 of smaller diameter than that of the central aperture 26 in the spider's dished middle body portion 25, and a rivet head 29 at one end of the shank 28, the other end of said shank 28 having a hollow 30 to facilitate its being riveted over when the glide is attached to an article of furniture.

Having described the individual parts of the glide reference is now made particularly to Figures 7 through 10 of the drawings, which illustrate the method of assembling the parts to each other and to a chair. The outer shell 18 is placed

in the form or die 31 of a suitable press as shown in Figure 7 and the rivet 19 is placed head downward in the center of the shell 18. The spider 20 is next inserted in the shell with its leg portions 27 resting on the bottom of the shell. The shank 28 of the rivet projects upwardly through the central aperture 26 in the spider. The press punch 32, which has a suitable central cavity 33 therein, is next forced downwardly thus spreading the legs 27 of the spider outwardly so that their outer extremities are forced into tight en-

engagement with the outer shell's peripheral retaining flange 23 as shown in Figure 8. The upwardly dished middle body portion 25 of the spider 20 thus forms with the downwardly dished middle body portion 22 of the outer shell, a generally 5 spheroidal compartment 34 in which the rivet's head 29 is freely movable. The shank 28 of the rivet 18 is likewise freely movable in the central aperture 26 of the spider, thus providing for a limited universal movement of the rivet relative 10 to the outer shell and spider members.

The punch 32 is next removed, and the annular rubber cushion 21 is placed in position adjacent the spider 20, circumscribing the rivet's shank 19, and extending somewhat above the upper rim of the outer shell 18. The article of furniture is next placed in position with its flange 16 adjacent the upper surface of the rubber cushion 21 and with the rivet's shank 28 extending upwardly through an aperture 35 in said flange 16. The riveting head 36 of the press is then forced downwardly as illustrated in Figure 9, said head first squeezing the rubber cushion 21 and then spinning over the upper end of the rivet 18 while the rubber cushion is squeezed between the article of furniture and the spider 20 of the glide. The parts are thus finally assembled.

It is to be particularly noted that after final assembly the rubber cushion 21 remains "compressed" or squeezed between the chair frame 11 and the spider 20, and it thus normally urges the shell and spider of the glide away from the chair so that the rivet's head 29 normally engages the underside of the spider's upwardly dished middle portion as seen in Figure 10, wherein the double arrows indicate the forces exerted by the cushion 21.

It will be seen that when the chair is occupied, the displaceable quality of the rubber cushion permits universal movement of the chair and rivet relative to the outer shell and spider of the glide. The chair can thus be tipped rearwardly as indicated in Figures 4 and 5, while the outer shell 18 of the glide remains in approximately the same position on the floor with its relatively flat middle portion contacting the floor. Thus the somewhat sharper curled edges or shoulders of the glide do not normally come in contact with the floor, and there is little likelihood of the glide's making any impression in a composition or linoleum floor. This is particularly important with linoleum floors wherein too much mastic has been spread under the linoleum, as such floors are more readily indented and marred.

It will thus be seen that the invention provides a novel furniture glide having a unique limited universal movement relative to the article of furniture to which it is attached, for the purposes above described, and that the glide is of simple and rugged construction and attractive appearance. While but one specific embodiment of the invention has been herein shown and described, it will be understood that numerous details of the construction shown may be altered or omitted without departing from the spirit of the invention as the same is defined by the following claims.

I claim:

1. The method of making a furniture glide and

assembling it with an article of furniture, which method comprises: forming an outer shell with an upwardly and inwardly curled peripheral retaining flange; case-hardening said shell; placing a rivet in the shell with its head adjacent the center of the shell and its shank extending upwardly therefrom; forming a spider with an upwardly dished centrally apertured middle body portion and legs extending radially therefrom in downwardly-outwardly directions; placing the spider in the shell with the rivet's shank projecting upwardly through the spider's central aperture; compressing the spider downwardly to spread the legs thereof into tight engagement with the shell's peripheral retaining flange; placing an annular rubber cushion within the shell so that it circumscribes the rivet's shank and so that its bottom surface lies adjacent said spider and its top portion projects above the upper rim of the shell; placing the article of furniture adjacent the top surface of the rubber cushion with the upper end of the rivet's shank extending through an aperture in said article of furniture; exerting pressure downwardly on the article of furniture to squeeze the rubber cushion between the article of furniture and the spider and at the same time riveting over the upper end of the rivet's shank to secure the parts in assembly.

2. The method of making a furniture glide and assembling it with an article of furniture, which method comprises: forming an outer shell with an upwardly and inwardly curled peripheral retaining flange; placing a rivet in the shell with its head adjacent the center of the shell and its shank extending upwardly therefrom; forming a spider with an upwardly dished centrally apertured middle body portion and legs extending radially therefrom in downwardly-outwardly directions; placing the spider in the shell with the rivet's shank projecting upwardly through the spider's central aperture; compressing the spider downwardly to spread the legs thereof into tight engagement with the shell's peripheral retaining flange; placing an annular rubber cushion within the shell so that it circumscribes the rivet's shank and so that its bottom surface lies adjacent said spider and its top portion projects above the upper rim of the shell; placing the article of furniture adjacent the top surface of the rubber cushion with the upper end of the rivet's shank extending through an aperture in said article of furniture; exerting pressure downwardly on the article of furniture to squeeze the rubber cushion between the article of furniture and the spider and at the same time riveting over the upper end of the rivet's shank to secure the parts in assembly.

ERVING E. MORGAN.
